UNITED STATES PATENT OFFICE

RAYMOND M. DILLON, OF MIAMI, FLORIDA

LIFEBOAT LAUNCHING MECHANISM

Application filed May 1, 1931. Serial No. 534,341.

The invention relates to mechanism or means for launching life boats from ships.

The primary object of the invention is the provision of mechanism of the character specified, wherein the life boats upon a vessel will be automatically cast out therefrom for the launching of the same and can be released by a person within such life boats, the mechanism being of novel form to assure

10 safety and the positive release of the boat from the vessel, ship or the like.

Another object of the invention is the provision of mechanism of this character, wherein in the usual davits are dispensed with for the 15 supporting of the life boats upon a ship or vessel, and each boat can be carried overboard and lowered, and then released by the occupant within the life boat.

A further object of the invention is the 20 provision of mechanism of the character specified which is comparatively simple in construction, thoroughly reliable and efficient in operation, sturdy, durable and inexpensive to manufacture and install.

25 With these and other objects in view, the invention consists in the features of construction, combination and arrangement of parts, as will be hereinafter more fully described in detail, illustrated in the accompanying 30 drawings which disclose the preferred embodiment of the invention, and pointed out in the claims hereunto appended.

In the accompanying drawings:—

35 Figure 1 is a fragmentary sectional view through the hull or body of a ship, showing the mechanism constructed in accordance with the invention thereon for supporting life boats, one of the boats being extended overboard, while the other boat is resting upon the deck of the ship.

Figure 2 is a top plan view.

Figure 3 is a fragmentary sectional view on the line 3—3 of Figure 2, looking in the direction of the arrows.

45 Figure 4 is a sectional view on the line 4—4 of Figure 3, looking in the direction of the arrows.

50 Figure 5 is a sectional view on the line 5—5 of Figure 4, looking in the direction of the arrows.

Figure 6 is a sectional view on the line 6—6 of Figure 5, looking in the direction of the arrows.

Figure 7 is a fragmentary side elevation of the deck of the device for the life boat 55 when resting upon the deck, the device being shown by full lines in the position when the life boat is resting and by dotted lines when the boat is to be released from said device.

Figure 8 is a sectional view on the line 8—8 60 of Figure 1.

Figure 9 is a detail view, in section, showing a spring held pin for engaging and releasing the hook of one supporting cable.

Similar reference characters indicate corresponding parts throughout the several 65 views in the drawings.

Referring to the drawings in detail, A designates generally portions of superposed decks of a ship or vessel and on each deck 70 is arranged chock bearers 10, these being spaced the required distance apart and have swingingly connected thereto chocks 11 adapted to swing from perpendicular or vertical position to horizontal position, these 75 chocks being constructed to support a life boat 12, as shown in Figure 1 of the drawings. Pivoted at 13 with the axle of one of the chocks is a lever 14 which has pivoted thereto a link or connecting rod 15, the same 80 being pivoted to a crank 16 connected with the axle 17 of the other chock 11 of the pair disposed next to the outer side of the ship or vessel, so that on operating the lever, these 85 chocks can be swung from perpendicular position, which is their supporting relation to the boat 12, to a horizontal position whereby the said boat can be cleared or swung outwardly overboard of the ship or vessel.

Beyond the points of the bearers 10 of the chocks 11 and suitably anchored to each deck A and rising a proper height vertically therefrom are intermediate and outer uprights or posts 18 and 19 respectively which have arranged at their upper ends hangers 20 between which and slidably engaged therewith is a rack rail 21 in the form of an I beam constituting a crane for extension overboard of the ship or vessel, but normally inboard thereof. Suitably journaled in a pair of the 90 95 100

outer opposed uprights 19 is a power shaft 22 having fixed thereto cog pinions or gears 23 meshing with the toothed rack 24 on said rail 21 at its under side, the shaft 22 at one 5 end being fitted with a crank handle 25 so that the shaft can be rotated and in this way the cranes which are located beyond opposite ends of the boat 12 can be extended or retracted, as is clearly illustrated in Figure 1 10 of the drawings.

Mounted in any suitable manner near the outer ends of said rails 21 are brackets 26 to which are connected the blocks 27 of guide pulleys 28 and each pulley has trained there-over a raising and lowering cable 29, the outer end of which carries a hook 30, which latter engages with a suitable attaching device 31 at the end of the boat 12, the cable at the inner end being attached to a windlass 20 32 carried by the rail 21 near its inner end and cooperating with the windlass is a braking device 33, while the axle 34 of said windlass has fitted thereto a hand crank 35 so that on actuating the latter, the cable can be let 25 off or wound upon this windlass and in this manner, the boat 12 when overcast outboard can be raised and lowered, and finally dropped by releasing elements 31.

Each boat has mounted on one side thereof 30 either upon its gunwale 36 or below the same a pair of spaced releasing clamps, each comprising a block-like bearing 37 fastened to the boat 12 in any suitable manner and has 35 swingingly supported between pivot ears 38 a pair of opposed gripping and releasing jaws 39 provided with heel extensions 40, these jaws 39 being swingingly supported upon vertical pivots 41 engaged or mounted in the ears 38 and are adapted for releasable 40 engagement with an I-shaped rail or track 42 secured vertically to the outer face of the hull of the ship or vessel, it being understood, of course, that a pair of these rails is positioned on the hull in confronting relation to 45 the clamps on the boat 12 so that when the boat is lowered into the path of the rails 42, the clamps can engage therewith to lock the boat thereto.

Journalized centrally in the bearings 37 are 50 stud axles 43, each being projected interiorly of the boat 12 and at their inner ends are fitted with arms 44 to which is pivoted a connecting rod 45 so that the pair of arms can be shifted in unison. The rod 45 is connected at 46 with a throw lever 47 pivoted at 48 to a bracket mounted interiorly of the boat 12 and this lever 47 is manually operable.

On the stud axles 43, within the bearings 37, are cross heads 49 to which are pivotally 60 connected at opposite ends thereof links 50, these being also pivoted to resisting blocks or retaining members 51 adapted to co-act with the heel extensions 40 of the jaws 39 on the closing of the latter to maintain such 65 jaws in clamping position on the rail 42

when the said blocks or members 51 have been extended, the lever 47 being operable to extend or retract the blocks or members 51 and when in retracted position, the heel extensions 40 of the jaws will clear the said blocks or members 51 whereby the jaws will freely open and thus release the clamps from the rails 42.

The boat is lowered down the side of the ship on the rails, to a safe distance from the water. Then as the ship rolls back to the side on which the life boat is suspended, the life boat is released from the rails 42 and swings away from the ship by reason of the list of the ship. Then, at the proper moment, when the life boat has swung away from the vessel as far as it will (depending upon the degree of roll and at the moment when the life boat is close to the water) the cable release elements in the ends of the life boat are tripped and the life boat is dropped to the water.

What is claimed is:—

1. The combination with a life boat, of a support adapted to be arranged on board a ship and for suspending said boat overboard, means on the exterior of the ship and extending upwardly along the hull, these means constituting guiding elements, and means on the boat comprising pairs of pivoted jaws for slidably engagement with the guiding elements when the boat is lowered.

2. The combination with a life boat, of a support adapted to be arranged on board a ship and for suspending said boat overboard, means on the exterior of the ship and means on the boat for retaining said boat engaged with the means first named when the boat is lowered, and means for the releasing of said boat from the ship by an occupant within the boat.

3. The combination with a life boat, of a support adapted to be arranged on board a ship and for suspending said boat overboard, means on the exterior of the ship and on the boat to retain the latter engaged therewith when said boat is lowered, means for the releasing of said boat from the ship by an occupant within the boat, and chocks inboard of the ship for the resting of the boat therein and releasable to free the latter.

4. The combination with a life boat, of a support adapted to be arranged on board a ship and for suspending said boat overboard, means on the exterior of the ship and on the boat to retain the latter engaged while said boat is lowered, means for the releasing of said boat from the ship by an occupant within the boat, chocks inboard of the ship for the resting of the boat therein and releasable to free the latter, and means for controlling the support.

5. The combination with a life boat, of a support adapted to be arranged on board a ship and for suspending said boat overboard,
